UNITED STATES PATENT OFFICE.

HARRY N. COVELL, OF NEW YORK, N. Y., ASSIGNOR TO LIDGERWOOD MANUFACTURING COMPANY, OF NEW YORK, N. Y., A CORPORATION OF NEW YORK.

ROPE-WINDING ENGINE.

1,042,090.

Specification of Letters Patent.

Patented Oct. 22, 1912.

Application filed December 19, 1910. Serial No. 598,158.

To all whom it may concern:

Be it known that I, HARRY N. COVELL, a citizen of the United States, and a resident of New York city, borough of Brooklyn, in the county of Kings and State of New York, have invented certain new and useful Improvements in Rope-Winding Engines, of which the following is a specification.

My invention relates broadly and generally to new and useful improvements in rope winding engines and more particularly contemplates a structure adapted for use as a towing engine; that is, an engine including a drum adapted to be mounted on a towing vessel, the drum being arranged to have the towing line wound thereon, and operable to take up or let out the line, as may be desired, or to hold the same at a constant length.

The invention consists in the improved construction of parts and their arrangement in operative combination to be fully described hereinafter and the novelty of which will be particularly pointed out and distinctly claimed.

I have fully and clearly illustrated my invention in the accompanying drawings to be taken as a part of this specification and wherein—

Figure 1 is a view in side elevation of an exemplification of my invention. Fig. 2 is a top plan view partly in section of a towing engine embodying my invention. Fig. 3 is an enlarged detailed sectional view taken through a winding drum adapted to have a rope wound thereon.

Referring to the drawings by characters of reference, A designates a substantial bed-plate or base frame of such dimensions and design as to adapt it to the purposes for which it is intended and upon which the various operative parts of the engine are arranged. The specific construction of this bed-plate is capable of wide variation, but I prefer that it consist of a substantial casting comprising longitudinal side members 1, 2, joined at their ends by end members 3, 4, said frame being provided with lateral extensions 5, 6 at one end thereof. The frame is braced by a transverse member 7

which is joined to the end member 3 by a member 8 arranged parallel to the said end extensions.

Rising from the end extensions 5, 6 and the member 7 are pillars 9, 10, 11, each of which is provided at its upper end portion with a bearing 12, said bearings being in alignment with each other and receiving a horizontally disposed shaft 13 which extends transversely of the frame.

By this arrangement it will be seen that the shaft is divided into two portions disposed respectively on opposite sides of the pillar 10, and on the shaft sections, respectively, are mounted driving gears 14, 15, 65 said gears being arranged on opposite sides of the pillar 10 and preferably closely adjacent the same. These gears 14, 15 respectively mesh with pinions 16 and 17 mounted on a horizontally disposed power shaft 18 70 having bearings in the side members 1, 2, as shown at 19, the ends of the shaft projecting beyond said side members and having mounted thereon crank disks 20, 20, which are connected to piston 21, 21 which are 75 in turn connected to the sliding cross heads 22, 22, operated by the pistons 23, 23 of fluid pressure cylinders 24, 24, whereby the crank shaft may be driven to rotate the driving gears 14 and 15. Any suitable valve 80 mechanism for controlling the fluid pressure cylinders may be employed.

The particular fluid pressure engine and its controlling means is illustrated merely as one type of motor which may be conveniently used for generating the necessary power to drive the power shaft 18 and I wish it understood that I do not desire to be limited to any particular type of motor for this purpose.

In view of the fact that the specific construction of the engine forms no part of my present invention, I do not deem it necessary to enter into any more detailed description of the same, except to say that 95 it is preferably of the type which will permit the reversal of the direction of rotation of the driving shaft, although this is not absolutely essential.

Mounted on the side members 1, 2 be- 100

2
tween a transverse plane occupied by the engine cylinders and the power shafts are pillars 25, 25 having bearings 26, 26 in which is mounted a horizontally disposed drum shaft 27 upon which is arranged a driving gear 28, which meshes with a pinion 29 on the power shaft. By the arrangement shown and described the driving shaft may operate to simultaneously drive all of the driving gears 14, 15 and 28.

10 Mounted upon each of the sections of the shaft 13 and upon the shaft 27 is a rope drum adapted to receive a towing line which connects the towing vessel to the tow, and as these drums are all of the same construction, a description of one will be sufficient to give a clear idea of my invention.

Each drum consists of a barrel 30 having end flanges 31, said drums being arranged 20 to slide longitudinally of their shafts toward and away from their respective driving gears, so that said drums may be connected or disconnected from said driving gears. The adjacent faces of the drums and 25 their driving gears are provided respectively with annular friction rings 31^a, 31^b by means of which sufficient friction may be generated between the drums and their gears whereby the gears will drive the 30 drums. Adjacent the end of each drum opposite to that which is adapted to frictionally engage with the driving gear is a fixed friction surface 32 preferably annular in form, and concentric to the drum shaft, 35 said friction surface being provided with a friction ring 33 adapted to frictionally engage with a co-acting friction ring 34 carried by the adjacent end flange of the drum.

40 Means is provided for moving each drum longitudinally of its shaft so as to place it in frictional contact with its driving gear to be driven therefrom to take up or pay out the rope and to move it out of driving 45 contact with its driving gear to place it in engagement with the fixed friction surface whereby the drum will be held against revolution. I will now proceed to describe this means which also contemplates the provision 50 of an arrangement whereby the drum, when in engagement with the fixed friction surface, may slip relative thereto to prevent disastrous results which might ensue from an excessive pull on the towing line.

55 Mounted on the drum shaft is a thrust sleeve 35 which is arranged so as to rotate about the shaft and to move longitudinally thereof, the outer end of the sleeve being threaded to coöperate with corresponding 60 threads, as shown at 36, arranged in the hub 37 of the fixed friction surface, the arrangement being such that a rotation of the sleeve 35 will serve to move the same either toward or away from the end of the drum. The 65 opposite end of the sleeve 35 extends to a

point adjacent the hub or barrel of the drum where it is provided with an end flange 38 separated preferably from the end of the drum by an antifriction washer 39. Surrounding the shaft and sleeve 35 is a chamber 40 having at one end an abutment 70 consisting preferably of an inwardly turned flange 41 closely approaching the outer surface of the sleeve and said chamber at its opposite end being provided with an outwardly projected flange 42, which is adapted to be adjustably connected to the head of the drum by means of bolts 43 and nuts 44, this end of the sleeve being preferably slidable over a projection 45 on the head of the drum. Arranged within this chamber and surrounding the sleeve 35 is a coil spring 46, the ends of which respectively abut the flange 41 and a washer 47 adjacent the flange 38, said washer being limited in its movement toward the spring by engagement with an annular shoulder 48 in the inner face of the sleeve 40. The washer 47 is preferably separated from the flange 38 on the sleeve by means of an anti-friction washer 49, all as clearly shown in Fig. 3 of the drawings.

Any suitable means may be employed for rotating the sleeve 35 to cause it to move along the drum shaft, but the following is a simple and effective way of accomplishing this result: Mounted on the sleeve 35 and keyed thereto is a gear 50 which meshes with a pinion 51 mounted on a horizontally disposed shaft 52 journaled in a bearing 53 preferably mounted on or formed in the fixed friction structure, said shaft being rotatable by means of a hand lever 53^a.

I will now proceed to describe the operation of the invention: If it is desired to place one of the drums in engagement with its driving gear so as to take up, or positively pay out the towing line, the hand lever 53 is operated to so rotate the shaft 52 that said sleeve 35 will be thrust into engagement with the head of the drum and the latter will thereby be moved longitudinally of its shaft to place its friction ring in contact with the friction ring on the driving gear, whereby the drum may be revolved in either direction according as to the direction in which the power shaft is driven by the engine. When the desired amount of towing line is taken up or paid out, the drum is disconnected from its driving means and placed in frictional engagement with the fixed driving surface, at its opposite end, and in order to do this, the hand lever 53 is moved in the opposite direction from that above described, so that the sleeve is moved in the opposite direction, and acting through the flange 38, spring 46 and flange 41 will move the drum toward the fixed friction surface to place the friction rings on the drum and said sur- 130

face in contact to hold the drum against the paying out of the line.

It will be understood that by provision of the spring between the sleeve 35 and the drum the latter will be held in engagement with the fixed friction element with a yielding contact, so that should the pull on the line exceed that determined upon, the drum may slip relative to the fixed friction, to prevent the breaking of the line or injury to the towing engine. The degree of the friction between the drum and the fixed friction element may be determined by the degree of compression given the spring, this being accomplished by adjustment of the nuts 44 on the bolts 33, the nuts being screwed up to increase the force of the spring and let out to lessen it. For example, should the degree of pull on the line be determined as being 3000 pounds, then the force of the spring is regulated at or above 3000 pounds, so that the drum cannot slip so long as the pull on the line remains at or below 3000, but it is obvious that should the pull exceed the amount set, then the drum will slip relative to the friction surface. If it should be desired that the drum be held in engagement with the friction surface with a higher degree of friction than can be given by the spring without adjusting the compression of the nuts 44, then the sleeve in moving the drum toward said friction element is moved far enough to place the washer 47 in engagement with the shoulder 48 in the sleeve 40, whereby the drum will be positively moved into engagement with said friction element.

While I have shown an arrangement embodying three friction drums, I wish it understood that I do not desire to be limited to such an arrangement of any particular number of drums, nor do I desire to be limited in any way to a towing engine as the invention is capable of use and will prove valuable in connection with different types of rope winding engines.

Having thus described my invention, what I claim as new and desire to secure by Letters Patent is:—

50 1. In a rope engine, a revolute drum, a revolute driving element, a fixed friction element, a thrust means movable in one direction to couple the drum to the driving element, and movable in the other direction to uncouple the drum from the driving element and move it into engagement with the friction element, means to provide a positive engagement between the thrust means and drum when moving the latter to couple it to the driving element, and a cushion connection operating between said thrust means and drum when the latter is moved to engage the friction element.

2. In a rope engine, a revolute drum and means for driving the same, a fixed friction

surface, means for placing the drum in frictional contact with said surface, and a spring between said means and the drum.

3. In a rope engine, a drum, a driving element, means for connecting the drum and driving element to drive the drum, a fixed friction element adjacent one end of the drum, means for moving the drum into engagement with said fixed friction element and a spring adapted to exert its thrust expansively between said means and drum. 75

4. In a rope engine, a shaft, a drum and a driving gear on the shaft, a fixed friction element, means for placing the drum and driving element in driving connection, means for placing the drum in engagement with the fixed friction element, a spring between said means and the drum, and means whereby the drum may be positively placed in contact with the friction element. 80

5. In a rope engine, a shaft, a drum and a driving element on the shaft, means for connecting the drum and element to drive the drum, a fixed friction element concentric with the shaft, means for moving the drum into engagement with the driving element, and means for disconnecting the drum and driving element and connecting the drum to the fixed friction element, and yielding means to permit slip of the drum relative to 95 said friction element.

6. In a rope engine, a drum, a driving element, means for connecting the drum and driving element to drive the drum, a fixed friction element adjacent one end of the drum, means to disconnect the drum from the driving element and place the drum in engagement with said friction element, means to provide a yielding engagement of the drum with said friction element, and means for positively engaging the drum with said friction element. 100

7. In a rope engine, a revolute drum, a revolute driving element, means for coupling and uncoupling said drum and element, a fixed braking surface, means for moving and holding the drum in engagement with said surface, when the drum and driving element are disconnected and a spring between said means and drum placed under compression when said drum and surface are engaged, and providing a yielding engagement between the drum and said surface. 110

8. In a rope engine, a revolute drum and means for driving the same, a fixed friction element, means for disconnecting the drum from the driving means and for moving the drum into contact with the fixed friction element, a spring between said moving means and the drum, and means whereby said spring is placed under compression when the drum is engaged with the fixed friction element. 120

9. In a rope engine, a revolute drum and 130

- means for driving the same, a fixed friction element, means for disconnecting the drum from the driving means and placing it in engagement with the fixed friction element, 5 a spring between said means and the drum, and means for adjusting the force of the spring.
10. In a rope engine, a revoluble drum and means for driving the same, a fixed friction element, means for disconnecting the drum from the driving means, means for moving the drum into contact with the fixed friction element, and a spring between said moving means and the drum.
15. 11. In a rope engine, a revoluble drum, a fixed friction element adapted to be engaged by the drum, an element for moving the drum against said friction element, a spring between said element and drum, an inclosure 20 connecting the spring and drum, and means for adjusting the inclosure relative to the drum to regulate the force of the spring.
12. In a rope drum, the combination of a shaft, a drum on the shaft, a fixed friction 25 element, a projection on the drum between the drum and the fixed friction element, a thrust element surrounding the shaft and inclosed by said projection, and a spring between said projection and the thrust element whereby a yielding connection is provided between the drum and its moving 30 means and the drum is held in yielding contact with the friction element.
13. In a rope drum, a shaft, a drum on the shaft, a fixed friction element adjacent 35 an end of the drum, means for moving the drum into engagement with said friction surface comprising a thrust sleeve surrounding the shaft, a casing on the drum receiving said sleeve, a spring in the casing compressible 40 between the sleeve and the casing, and means for moving the sleeve lengthwise of the shaft.
14. In a rope drum, a shaft, a drum on the shaft, a fixed friction element adjacent 45 one end of the drum, and means for moving the drum into engagement with said friction surface comprising a thrust sleeve surrounding the shaft and having a projection, a casing secured to the drum and receiving the

projection on the sleeve, said casing also having a projection, a spring between the projection on the sleeve and the projection on the casing, and means for moving the sleeve longitudinally of the shaft. 55

15. In a rope drum, a shaft, a drum on the shaft, a fixed friction element adjacent one end of the drum, and means for moving the drum into engagement with the fixed friction element comprising a thrust sleeve 60 threaded into a fixed support, and having a projection, a casing on the drum receiving the sleeve and having a projection, a spring inclosed within the casing between said projections, and means for rotating the sleeve 65 to cause it to move longitudinally of the shaft.

16. In a rope drum, a shaft, a driving element on the shaft, a fixed friction element surrounding the shaft, a drum between 70 the driving element and the fixed element, and means for moving the drum longitudinally of the shaft to engage and disengage the same from the driving element and the friction element said means comprising a 75 thrust element surrounding the shaft and engaging the drum, a casing on the drum receiving the thrust element, and a spring between the thrust element and said casing.

17. In a rope drum in combination, a 80 shaft, a driving element, a drum on the shaft, a fixed friction element adjacent one end of the drum, and means for moving the drum toward and away from said friction element comprising a thrust element mounted 85 on the shaft and movable longitudinally thereof between the drum and the fixed element, a casing on the drum receiving the thrust element, a spring between the thrust element and the casing, and means whereby 90 a positive connection is established between the thrust element and the casing.

In witness whereof I have signed my name to this specification in the presence of two subscribing witnesses.

HARRY N. COVELL.
